Patented Mar. 25, 1975

234,621

WALL MOUNTED LIGHTING FIXTURE OR SIMILAR ARTICLE

Henry Muller, Rego Park, N.Y., assignor to Lightolier
Incorporated, Jersey City, N.J.

Filed Oct. 9, 1973, Ser. No. 404,753

Term of patent 14 years

Int. Cl. D26—05

U.S. Cl. D48—4 B

FIG. 1

FIG. 2

FIG. 3

FIG. 4

FIG. 6

FIG. 5

FIG. 1 is a perspective view of a wall mounted lighting fixture or similar article showing my new design;

FIG. 2 is a side elevational view thereof;

FIG. 3 is a front view thereof;

FIGS. 4 and 5 are respectively top and bottom end views thereof;

FIG. 6 is a rear view thereof.

I claim:

The ornamental design for a wall mounted lighting fixture or similar article, substantially as shown.
